UNITED STATES PATENT OFFICE

LE ROY SMELKER, OF DAYTON, OHIO, ASSIGNOR TO FRIGIDAIRE CORPORATION, OF DAYTON, OHIO, A CORPORATION OF OHIO

COLLAPSIBLE STAND

Application filed July 13, 1929. Serial No. 378,188.

This invention relates to collapsible stands and particularly to portable stands.

One of the objects of the present invention is to provide a strong stand which will be 5 light in weight and which may be collapsed and folded into a small compact bundle.

Another object of the invention is to construct a collapsible stand of material which will not be affected by climatic changes.

10 More specifically it is an object of the invention to provide a collapsible stand which will serve either as a motion picture screen or an illustrating device for charts or the like.

Further objects and advantages of the 15 present invention will be apparent from the following description, reference being had to the accompanying drawings, wherein a preferred form of the invention is clearly shown.

20 In the drawings:

Fig. 1 is a front elevational view of my improved collapsible stand.

Fig. 2 is a side elevational view thereof.

Fig. 3 is a sectional view taken on the line 25 3—3 of Fig. 2 showing the stand supporting members.

Fig. 4 is an enlarged sectional view taken on the line 4—4 of Fig. 1 showing a hinged connection of one of the lower braces and 30 the detachable connection of one of the upper braces.

Fig. 5 is an enlarged vertical section thru the standard taken on the line 5—5 of Fig. 1.

Fig. 6 is an enlarged horizontal section 35 taken on the line 6—6 of Fig. 1.

Fig. 7 is an enlarged vertical section taken on the line 7—7 of Fig. 1.

Figs. 8, 9, 10 and 11 show various parts of the stand with the braces secured thereto 40 collapsed, and

Fig. 12 is a view of a portable bundle which contains all the collapsed parts of the stand shown in Figs. 8, 9, 10 and 11.

Referring to the drawings, 10 designates 45 a standard comprising detachable portions 11 and 12. Portions 11 and 12 of the standard are preferably made of hollow tubular metal and have their ends slotted as at 13 to receive brackets 14 and 15 mounted on angle iron cross-pieces 16 and 17 providing out-

wardly extending arms which are adapted to be secured to the standard 10. Lower portion 12 of the standard has its upper end threaded to receive internal threads provided on the upper portion 11 of the standard. The 55 angle iron cross-piece 17 is firmly secured to the standard 10 by threading the portions 11 and 12 tightly together. Figures 5 and 6 more clearly show this method of securing the angle iron cross-piece 17 to the standard 10. 60 Angle irons 18 and 19 hinged to the lower end of the standard 10 by pin 20 extend outwardly and have angle iron members 21 and 22 disposed at right angles thereto and hinged at 23 for supporting the stand. 65

The upper angle iron 16 has brackets 25 secured thereto from which a roll screen 26 is dependingly supported. The screen 26 is painted white and is similar to the ordinary window shades used in houses and serves as 70 a screen upon which pictures or illustrations may be projected. Hooks 27 mounted on suitable fabric straps 28 which are secured to the angle iron 16 provide a mounting for dependingly supporting display charts. A 75 writing pad may be supported on the hooks 27 when it is desired to use the stand for illustrating purposes other than by the display charts. The rivets which secure straps 28 to the angle iron 16 also secure a lattice 29 80 thereto. The location and method of securing the screen 26, hook 27, straps 28, and lattice 29 is more clearly shown in Fig. 7. The lattice 29 comprises a plurality of narrow slats 29a held together by cords 29b alternately woven therearound. The lattice provides a backing for display charts or for a writing pad which may be suspended from the hooks 27 thereby preventing puncturing of the charts while illustrating with pointers 85 or the like.

To render the stand more rigid I have provided a plurality of strap iron braces which may be hinged or pivoted to the various parts of the stand and which are adapted to be collapsed and rolled up with other parts thereof. I provide a brace 31 on each side of the standard 10 having their upper ends pivoted or hinged to the ends of the angle iron cross-piece 16 and their lower ends detachably con- 90 95 98

nected with studs 32 secured to the ends of the lower angle iron cross-piece 17. The studs 32 are provided with a shank portion 34 adapted to receive slots 35 provided in the braces 31. The braces 31 are also provided with hinged joints 36 which permit these braces to be collapsed and folded adjacent the angle iron cross-piece 16. Braces 38, pivoted or hinged to the angle iron cross-piece 17 are twisted so that slots 39 at the ends thereof will engage studs 40 located on the angle iron members 21 and 22. The angle iron members 21 and 22 have braces 41 pivoted or hinged thereto and provided with slots 42 adapted to engage studs 43 located on the braces 38 below the twisted portion thereof. All the braces are made slightly shorter than the distance between their connecting points so that they will be under slight tension when assembled thereby providing a rigid structure. The hinged connections of the braces with the various other parts of the stand permit them to be folded and rolled into a compact portable package. When it is desired to move the stand from one locality to another it may be disassembled and rolled into a compact package.

Dismantling of the stand is accomplished in the following manner. Braces 31 are manipulated so that slots 35 therein move out of engagement with the studs 32. Hinged joints 36 in the braces 31 then permit the braces to be folded against the angle iron cross-piece 16. The cross-piece 16 carrying the screen 26, supporting hooks 27 and the lattice 29 may then be removed from the upper end of standard 10. (See Fig. 8.) After the cross-piece 16 has been dismantled the upper portion 11 of standard 10 may be unscrewed from the lower portion 12. (See Fig. 9.) The separation of portions 11 and 12 of the standard 10 then permits the removal of angle iron cross-piece 17 from the standard. To remove the cross-piece 17 braces 41 must be manipulated to disengage slots 42 formed therein from studs 43. Braces 38 are then manipulated to disengage slots 39 formed therein from the studs 40 secured to angle iron members 21 and 22. Braces 38 are then folded against the cross-piece 17 and removed therewith from the portion 12 of the standard (see Fig. 10). There now remain only portion 12 of the standard and the standard supporting members to be collapsed. The braces 41 now being free are folded against angle iron members 21 and 22 which are hinged to the angle irons 18 and 19. The members 21 and 22 are then moved about their hinge 23 so as to be in alignment with the angle irons 18 and 19. This movement is shown by the dotted line positions of members 21 and 22 in Fig. 3. The angle irons 18 and 19 are then moved upwardly about their hinge 20 so as to be in alignment and against the portion 12 of the standard 10 (see Fig. 11). The collapsed

parts of the stand shown in Figs. 9, 10 and 11 are then placed upon the lattice 29 and rolled into a compact bundle. The lattice 29 is of sufficient length and width to completely enclose all collapsed parts of the stand including the cross-piece 16 to which the lattice is secured thereby providing a cover for the bundle. If desired a separate water proof cover may also be provided for the bundle. The cross sectional contour of the cross-piece 16 protects the screen 26 from being damaged when the parts are rolled together into a bundle. The bundle and its contents is then kept intact by firmly tightening carrying straps 45 therearound (see Fig. 12). A handle 46 is interposed between straps 45 to permit the bundle or package to be readily picked up and carried.

All the parts of my improved collapsible stand are made of as light a material as obtainable so that the bundle or package will not be excessive in weight. Likewise I have provided a collapsible stand of such construction that will eliminate non-fitting of the various parts due to climatic changes. While I have described the operation of dismantling the stand it will be understood by those skilled in the art that the setting up or assembling operation is accomplished in reverse order to that described. It is apparent from the foregoing description that I have provided a novel stand which may be used by salesmen, lecturers and demonstrators either as a motion picture screen, black board or display device and which may readily be collapsed and carried from one locality to another.

While the form of embodiment of the invention as herein disclosed constitutes a preferred form, it is to be understood that other forms might be adopted, all coming within the scope of the claims which follow.

What is claimed is as follows.

1. A collapsible stand comprising in combination, a standard having separable lower and upper portions, a cross-piece detachably secured between said portions and providing outwardly extending arms, a cross-piece detachably secured to the upper end of said standard and providing outwardly extending arms, means pivotally mounted to the standard and extending outwardly therefrom adapted to maintain the standard in a vertical position, a brace on each side of the standard extending between the second named arms and said first named arms, said second named arms having a mounting for dependingly supporting a screen, and means on said second named arms for dependingly supporting display means.

2. A collapsible stand comprising in combination, a standard having separable lower and upper portions, a cross-piece detachably secured between said portions and providing outwardly extending arms, a cross-

piece detachably secured to the upper end of said standard and providing outwardly extending arms, means pivotally mounted to the standard and extending outwardly therefrom adapted to maintain the standard in a vertical position, a brace on each side of the standard extending between the second named arms and said first named arms, said second named arms having a mounting for dependingly supporting a screen, means on said second named arms for dependingly supporting display means, and means depending from said second named arms providing a backing for said display means.

5 to the second named arms and detachably connected with said first named arms, said second named arms having a mounting for dependingly supporting a screen, and means on said second named arms for dependingly supporting display means.

10 6. A collapsible stand comprising in combination, a standard having separable lower and upper portions, a cross-piece detachably secured between said portions and providing outwardly extending arms, a cross-piece detachably secured to the upper end of said standard and providing outwardly extending arms, supporting means adapted to maintain the standard in a vertical position, a hinged

17 display means.

3. A collapsible stand comprising in combination, a standard having separable lower and upper portions, a cross-piece detachably secured between said portions and providing outwardly extending arms, a cross-piece detachably secured to the upper end of said standard, and providing outwardly extending arms, means pivotally mounted to the standard and extending outwardly therefrom adapted to maintain the standard in a vertical position, each of said pivotally mounted means having a member pivotally secured thereto and extending therefrom, a brace on each side of the standard extending between the first named arms and said members, a brace extending upwardly from said members and engaging said first named brace, a brace on each side of the standard and extending between the second named arms and said first named arms, said second named arms having a mounting for dependingly supporting a screen, means on said second named arms for dependingly supporting display means, and means depending from said second named arms providing a backing for said display means.

45 4. A collapsible stand comprising in combination, a hollow metal standard, an angle iron secured to the upper end of said standard and extending outwardly from each side thereof, angle iron supporting members pivotally secured to the lower end of said standard and adapted to maintain the standard in a vertical position, said first named angle iron having a mounting for dependingly supporting a screen, hooks on said first named angle iron for dependingly supporting display means, and a lattice depending from said first named angle iron providing a backing for said display means.

50 In testimony whereof I hereto affix my signature.

55 LE ROY SMELKER.

5. A collapsible stand comprising in combination, a standard having separable lower and upper portions, a cross-piece detachably secured between said portions and providing outwardly extending arms, a cross-piece detachably secured to the upper end of said standard and providing outwardly extending arms, supporting means adapted to maintain the standard in a vertical position, a brace on each side of the standard pivotally secured
